UNITED STATES PATENT OFFICE.

THOMAS FENWICK, OF NEW YORK, N. Y.

EXCAVATOR.

No. 901,431.

Specification of Letters Patent.

Patented Oct. 20, 1908.

Application filed January 14, 1907. Serial No. 352,235.

To all whom it may concern:

Be it known that I, THOMAS FENWICK, a citizen of the United States of America, residing at New York, in the county of New York and State of New York, have invented new and useful Improvements in Excavators, of which the following is a specification.

The invention relates to an improvement in excavators of that class employing a plurality of tools operated in a circular plane 10 from a common drive shaft.

The main object of the present invention resides in the production of a rotary excavator carrying a series of oppositely extending cutting or digging tools, said tools being removably connected to the main or drive shaft whereby to permit their adjustment to vary the cutting depth or to permit their substitution with tools of a different character.

Another object of the invention is the provision of an excavator so constructed as to be readily operated by a self propelling engine of any usual or preferred type, the parts being arranged to permit the engineer to have 20 complete control of the excavator in operating the tools, propelling the excavator in any direction, and operating one set of tools without regard to the other.

The invention will be described in the following specification, reference being had particularly to the accompanying drawings, in which:—

Figure 1 is a view in front elevation of an excavator constructed in accordance with my invention, Fig. 2 is a vertical central sectional view of the same, Fig. 3 is a transverse sectional view taken through the drive shaft and protecting drum, illustrating particularly the means for connecting the tool's stem.

Referring particularly to the drawings, wherein similar reference numerals indicate like parts throughout the several views, my improved excavator, as shown, is of the double type, including end supporting frames 1 and 2, an intermediate supporting frame, as 3, and two independent series of tools. Each end supporting frame is constructed of angle iron, or other material, as preferred, including a rectangular base frame 4, mounted on ground wheels 5, front and rear standards 6 and 7, connected and braced by cross strips 8, the upper ends of the standards being connected to a rectangular head frame 9. The intermediate frame 3 includes 55 a head frame or canopy 10, and side stand-

ards 11 and 12, the latter corresponding to the standards 6 and 7, the standards 11 on one side of the intermediate frame being connected by suitable brace bars 13, the opposite standards 12 being similarly connected. 60 The lower ends of the respective pairs of standards are connected by cross bars 14, in which are pivotally mounted ground wheels 15, as clearly shown in Fig. 2.

Bearing blocks 16 are secured in the end frames 1 and 2, and similar blocks 17 are secured between each pair of standards of the intermediate frame. Drive shafts 18 are supported in the respective bearing blocks, the proximate ends of said shafts projecting 70 within the intermediate frame for connection with the motive power, as will presently appear. Each drive shaft is provided intermediate its respective bearings with an enlarged squared portion 19, designed to provide a tool support. The tools 20, of which there may be any desired number, comprise a tool proper 21, such as a shovel, pick, cutter, or any other desired form, designed for removable and adjustable connection with a 80 stem 22. The stem is preferably squared in cross section, except the relatively inner end, where it is of circular form and preferably threaded, as at 23, to any desired extent. The squared portions 19 of the drive shaft 85 are formed with openings 24 to receive the threaded ends of the stems, and nuts 25 and 26 co-operate with each stem beyond the opposing surfaces of the shaft, the former engaging the end of the stem beyond the surface of the shaft, and the latter engaging the stem beyond the opposing surface of the shaft, thus securing the stems to the shaft by two nuts engaging the stem and gripping the shaft between them. 95

The tools are preferably arranged in diametrically opposed relation, and in alternate order, as clearly shown in Fig. 1, so that the respective tools are arranged lengthwise the shaft, projecting at right angles thereto, in 100 alternate order and in opposite directions.

Each squared portion 19 of the drive shaft is protected by an enveloping casing or drum 27, of materially greater diameter than the shaft and co-extensive in length with the 105 length of the particular squared portion 19. The drum is formed with openings 28 for the stems of the tools, and is further formed with slots 29, alined with the respective securing nuts of the tool stems, the slots being so ar- 110

ranged and of such size to permit the introduction of a suitable wrench for manipulating the nuts 25 and 26 to adjust or remove the tools. The drum acts to thoroughly protect the drive shaft and the means for connecting the tools thereto, thereby adding to the effective life of these parts. Furthermore, the drum engages the tool stems beyond their connection with the shaft, thus effectively bracing the stems, one from the other, in an obvious manner.

As the motive power for the excavator I have illustrated an ordinary type of road engine, as 30, which, it is to be understood, is to illustrate any desired form of motive power. The road engine is propelled under its own power, being guided by suitable operation of the forward ground wheels 31. The ground wheels 5 and 15 of the excavator are, of course, of the pivot type, so that the direction of movement of the respective excavator frames may be readily and accurately controlled by the operator of the road engine. The road engine is provided with a driving wheel or gear 32, operated independently of the mechanism for propelling the engine, and said drive wheel is arranged to operate a crank shaft 34, the respective cranks of which are connected by coupling members 35 with the inwardly projecting ends 18 of the drive shaft of the excavators.

The intermediate frame 3 is of a width to permit the disposition of the road engine between the side bars thereof, and by the construction described the operator of the road engine may operate either or both sets of excavator tools, and may propel either excavator frame in either direction. I also contemplate the provision of traveling belts or carriers for receiving the material displaced by the excavating tools and operating said carriers from the road engine, or other motive power, whereby to remove the excavated material from beneath the excavating frame.

The operation of the excavator is fully disclosed by the drawings when read with the present specification, but in order to make the invention quite clear I recapitulate the *modus operandi* or method of working. The engine is of any type, somewhat similar to the road roller engine, so far as the guiding or steering apparatus is concerned, but it has compound or double action cylinders, first to propel and guide the engine to its work and then suspend that action and make the other or second action turn the shaft, which causes the cutters or other tools fixed thereon to rotate at a speed calculated from say twenty to sixty or more revolutions each minute according to the character consistency or resistance of the earth or dirt to be excavated. The shaft revolving carries the cutters or other excavating tools around with it, forming a circle. The length of stroke given to the tools by the nuts and threaded ends of

such tools will regulate the length of cut as well as the circumference of the circle.

The machine if employed against a vertical wall or bank of earth will cut a concave, which, however, may extend to the plane of the wheels or even still deeper if desired. The excavated earth is projected under the cutting machine very far beyond the radius of the line of cutters and keeps all under the cutters perfectly clear so there can be no accumulation or impediment. The excavated projected earth or dirt is received into any suitable receptacle, such as a hopper or bin attached to the engine running parallel in the rear of the cutters, or the dirt may be projected into movable or running bands or other forms of carriers in the form of stairs, a gauntlet or otherwise, say a system of dredger-buckets on endless chains. This is merely a detail to be varied by actual working operation and I do not lay claim to this as a material part of my present invention. The excavating tools in their circuit or revolution keep the excavated dirt clear of the machine rendering it impossible to form any obstruction to the free operation of excavation.

The operation of the machine as well as its size is regulated according to the character and class of work, and the quantity of available ground for movement. Thus where great width of space is available as in a canal, waterworks, clay pits or railroad cuttings the machine is operated from left to right and right to left again. The second operation across the face of earth will remove those portions or pillars of earth left from the first operation. I mean the blocks of ground which originally were opposite the engine and the standard or uprights beyond the line of cutters. So these operations will continue through the entire cutting. In more circumscribed spaces the engine being on pivot wheels, the same as the excavating machine, any remaining blocks will be cut by giving a slanting or angular direction or by simply backing and selecting a different position for the cutters or by altering the length of stroke or otherwise. It is impossible to define means for every operation until these are actually presented. Such operations will be guided and directed by the good common sense and high intelligence which the operator in charge should possess as in all other mechanical apparatus and movements.

The description and drawing are limited to the double type of rotary excavator, though it is obvious that the production of an excavator of the single type is produced by utilizing one of the end frames and the intermediate frames, as the end frames of the structure, and include only the set of tools and coöperating parts arranged between these frames.

The excavator described is of simple type

and few parts and, owing to the rotary movement of the tools, is highly effective for the purpose designed.

Having thus described the invention what I claim, is:—

1. A rotary excavator comprising separated supporting frames, a drive shaft mounted in each frame, and a series of tools secured in the shaft, said tools projecting in 10 diametrically opposed relation from the shaft.

2. A rotary excavator comprising spaced supporting frames, a drive shaft mounted in each frame, a series of tools secured in the 15 shaft and projecting in opposite directions therefrom, and a drum inclosing the shaft and formed with openings for the passage of the tools.

3. A rotary excavator comprising spaced 20 supporting frames, a drive shaft mounted in each frame, a series of tools secured in the shaft and projecting in opposite directions therefrom, and a drum inclosing the shaft and formed with openings for the passage of 25 the tools, said drum being of greater diametrical dimension than the shaft, whereby to brace the tools beyond the shaft.

4. A rotary excavator comprising a drive 30 shaft, end frames for supporting said shaft, said shaft being squared intermediate the frames, a series of tools including tools proper and stems secured thereto, means for securing the stems to the squared portion of the shaft, and a drum inclosing the squared

portion of the shaft, and bracing the tool 35 stems beyond the shaft.

5. A rotary excavator comprising a drive shaft, end frames for supporting said shaft, said shaft being squared intermediate the frames, a series of tools including tools proper 40 and stems secured thereto, means for securing the stems to the squared portion of the shaft, and a drum inclosing the squared portion of the shaft, and bracing the tool stems beyond the shaft, said drum being formed 45 with openings to provide access to the stem securing means.

6. A rotary excavator comprising separated supporting frames, a drive shaft mounted in each frame, and a series of tools 50 secured in the shaft, said tools projecting in diametrically opposed relation from the shaft, in combination with an engine connected to operate each frame and shaft.

7. A rotary excavator comprising separated supporting frames, a drive shaft mounted in each frame, and a series of tools 55 secured in the shaft, said tools projecting in diametrically opposed relation from the shaft, in combination with an engine connected to independently operate each frame and shaft.

In testimony whereof, I affix my signature in presence of two witnesses.

THOMAS FENWICK.
